RIM CONSTRUCTION FOR PIANOS

Wilbur M. Day, Cincinnati, Ohio, assignor to The
Baldwin Company, Cincinnati, Ohio

Application November 26, 1937, Serial No. 176,410

8 Claims. (Cl. 84—177)

My invention has reference to piano construction and more particularly to the construction of grand pianos of unusual shapes characterized by discontinuous rim curves and abrupt rim corners. They are in contrast to the appearance of the conventional grand piano, and offer to the decorative designer interesting possibilities for producing pianos of unusual and pleasing appearances. They present, however, certain structural problems.

One of these problems is that of constructing the piano rim. In the past the structural rims for grand pianos of unusual appearance have been formed from a number of segments, generally of wood, each shaped to its appropriate segmental form, these segments being glued together in lap and butt joints. While such a method of construction provides a grand piano of a desired appearance, it fails to provide, *per se*, a strong rim for the instrument. For, it is not entirely successful under the conditions of mechanical stress resulting from the fifteen to twenty tons of cumulative string tension in a modern piano, requiring thus additional bracing. Then, being comprised of various discontinuous glued joints, it is not entirely free from joint parting under varying conditions of weather. It is to be compared with the structural rim (variously called inner rim, soundboard rim, or acoustic rim) of the usual grand piano. There the structural rim is composed of a series of continuous laminae glued continuously to form a strong unit in a complex but unbroken curve, requiring large radii of curvature but possessing both structural and acoustic advantages.

It is therefore an object of my invention to provide a rim construction for pianos which retains the advantages of the usual grand piano rim but which is readily susceptible to external modifications.

It is another object of the invention to provide an exemplary grand piano of symmetrical appearance having a type of corner construction in keeping with the first object and having the fundamental advantages of a large soundboard area for its size and a strong, economical rim.

These objects and other objects which will be apparent to those skilled in the art on reading this specification, I accomplish by constructions and arrangements of parts which I shall now describe in detail. For clearance reference is had to the drawings wherein.

Figure 1 is a plan view of a symmetrical grand piano constructed according to the principles of

the invention, the lid being removed and the piano cut away partly to expose the rim;

Figure 2 is an elevational view of an exterior corner of the piano, as if viewed in a direction indicated by A in Figure 1;

Figure 3 is a cross-section of a corner, taken on the cutting plane B—B of Figure 1;

Figure 4 is an enlarged plan view of a corner with the top surface veneer removed from the outer rim and corner block; and

Figure 5 is an enlarged plan view of a modified form of corner, likewise with the top surface veneer removed from the outer rim and corner block.

With reference now in particular to Figure 1, a symmetrical grand piano comprises an inner or structural rim 1 of continuous wood laminations formed symmetrically with four corners each of large radii of curvature. Glued to the upper surface of the rim 1 is a soundboard 2. On top of the soundboard is placed a metal string-plate 3 securely attached to the rim 1 by screws as 4 extending through the soundboard into the rim. The plate 3 supports strings 5, 5' attached to the soundboard through bridges 6, 6'; and the piano contains a well-known pinblock and action parts (not shown). It will be noted that by reason of its shape the piano is of large soundboard area.

Enclosing the inner rim and attached thereto except at the corners is an outer rim 7 of lesser thickness than the inner rim 1 and composed likewise of continuous wood laminations. Since the rim 7 is of lesser thickness than rim 1, its radii at the four corners, shown and above mentioned, may be smaller than those of the rim 1; and thus more susceptible for the exterior addition of narrow conforming corner blocks 8 having sharp exterior corners. Between the two rims at the corners are wood filler blocks as 9.

It will be noted that the string-plate 3 extends into the four corners to be adjacent the outer rim 7 and to cover the filler blocks 9 (Figures 1 and 3). Moreover, the outer rim extends above the inner rim to form a casing for the piano (Figures 2 and 3).

A modified corner construction is shown in Figure 5. Here a corner block 8' and outer rim 7 are overlaid with a surface veneer 10.

Having thus described my invention, I claim:

1. A grand piano case including a support rim and a closure rim encompassing said support rim, each of said rims comprising a plurality of wood laminae respectively of the rim width, cemented together to form the rim thickness and

extending in length as a horizontal compound curve comprising curve portions of relatively small curvature interspaced with curve segments of relatively large outward convexity, said closure rim conforming to said support rim in said portions of relatively small curvature and secured thereto in said portions, said closure rim being of lesser thickness than said support rim and of greater outward convexity in said convex segments, whereby in said segments said closure rim is spaced apart outwardly from said support rim, and a plurality of wood corner members secured to the outer surface of said closure rim respectively at said convex portions, said members extending each the width of said closure rim and conforming to said closure rim in their surfaces of junction therewith, the exposed surfaces of said members forming tangential continuations of said closure rim portions of small curvature, whereby said members present line corners extending the width of said closure rim.

2. The structure as set forth in claim 1, including a plurality of wood filler blocks respectively in the spaces between corresponding said rim convex portions and secured to said rims, said blocks conforming in shape respectively to the spaces between corresponding said portions to fill said spaces.

3. The structure as set forth in claim 1, including a plurality of wood veneer sheets secured to the exposed surfaces of said closure rim and said corner members, said sheets being respectively of the width of said rim and said members and abutting end to end to cover effectively said rim and said members.

4. The structure as set forth in claim 1, including a plurality of wood filler blocks in the spaces between corresponding said rim convex portions and secured to said rims, said blocks conforming in shape respectively to the spaces between corresponding said portions to fill said spaces, and a plurality of wood veneer sheets secured to the exposed surfaces of said closure rim and said corner members, said sheets being respectively of the width of said rim and said members and abutting end to end to cover effectively said rim and said members.

5. A symmetrical grand piano case including a support rim and a closure rim encompassing said support rim, each of said rims comprising a plurality of wood laminae respectively of the rim width, cemented together to form the rim thickness and extending in length as a horizontal

compound curve comprising two end portions of similar shape, a middle portion symmetrically disposed with respect to said end portions, and two intermediate portions of similar shape extending respectively from adjacent an inner end of an end portion to adjacent an end of said middle portion, said portions being of relatively small curvature and interspaced with segments of relatively large outward convexity, said closure rim conforming to said support rim in said portions of relatively small curvature and secured thereto in said portions, said closure rim being of lesser thickness than said support rim and of greater outward convexity in said convex segments, whereby in said segments said closure rim is spaced apart outwardly from said support rim, and a plurality of wood corner members secured to the outer surface of said closure rim respectively at said convex portions, said members extending each the width of said closure rim and conforming to said closure rim in their surfaces of junction therewith, the exposed surfaces of said members forming tangential continuations of said closure rim portions of small curvature, whereby said members present line corners extending the width of said closure rim.

6. The structure as set forth in claim 5, including a plurality of wood filler blocks respectively in the spaces between corresponding said rim convex portions and secured to said rims, said blocks conforming in shape respectively to the spaces between corresponding said portions, to fill said spaces.

7. The structure as set forth in claim 5, including a plurality of wood veneer sheets secured to the exposed surfaces of said closure rim and said corner members, said sheets being respectively of the width of said rim and said members and abutting end to end to cover effectively said rim and said members.

8. The structure as set forth in claim 5, including a plurality of wood veneer sheets secured to the exposed surfaces of said closure rim and said corner members, said sheets being respectively of the width of said rim and said members and abutting end to end to cover effectively said rim and said members, and a plurality of wood filler blocks respectively in the spaces between corresponding said rim convex portions and secured to said rims, said blocks conforming in shape respectively to the spaces between corresponding said portions, to fill said spaces.

WILBUR M. DAY.
